(57) **CLAIM**

The ornamental design for a transmitter component of a charging system, as shown and described.

DESCRIPTION

FIG. 1 is an isometric view of a transmitter component of a charging system.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof; and,

FIG. 8 is an isometric view of the transmitter component of FIG. 1, shown positioned inside an in-ground installation bracket.

The broken lines in the drawings show portions of the transmitter component of a charging system and environmental subject matter that form no part of the claimed design.

1 Claim, 8 Drawing Sheets
